UNITED STATES PATENT OFFICE.

PAUL DE CRÉQUY, OF NEW BRIGHTON, ENGLAND.

AEROPLANE.

1,354,728.

Specification of Letters Patent.

Patented Oct. 5, 1920.

Application filed October 1, 1913, Serial No. 792,801. Renewed August 3, 1918. Serial No. 246,229.

To all whom it may concern:

Be it known that I, PAUL DE CRÉQUY, a citizen of France, and a resident of Belgrave, Wellington Road, New Brighton, 5 Cheshire, England, have invented certain new and useful Improvements in Aeroplanes, of which the following is a specification.

This invention which relates to aeroplanes 10 has for its object certain new features and improvements in existing ones, and for the better understanding of the invention reference may be had to the accompanying drawings in which—

15 Figure 1 is an end view of the frame and wings of any aeroplane showing some features of my invention. Fig. 1^a is a detail view hereinafter described.

Figs. 2, 2^a and 3 are details thereof.

20 Figs. 4 and 4^a show a modification of Fig. 1.

Fig. 5 illustrates an improved elevator or stabilizer which will act also as an automatic equilibrator, one being used at the 25 back also, if desired, but preferably only as a stabilizer. Fig. 6 is an end view of a portion of a biplane showing some of my improvements. Fig. 7 is a diagrammatic view 30 of a portion of my machine. Fig. 8 is an enlarged view of a portion of a monoplane showing the arrangement of my "air-slurries" in the wings or planes for descending.

Referring first to Figs. 1, 2, 2^a and 3, 1 is the frame, 2 the wings or planes which in 35 this case are articulated to the frame, near the vertical center thereof at each side, and 3 are the stays. It is well known that ordinary rigid stays frequently break, thereby being the cause of many accidents. Now to 40 prevent this I provide flexible stays by means of springs which may be of any suitable type but preferably those shown in Fig. 3, in which the springs are compressed by one or more pistons in a casing or tube as 45 shown. The important novelty is that these elastic stays, adequately extensible and on articulated wings, are used in conjunction with either a simple mode of gearing the wings directly together, as shown in Fig. 1^a 50 (in which the toothed wheels are on the same pivot as the wing articulations), or preferably in conjunction with cross connections for reciprocal transmission from wing to wing of any difference of air pressure 55 between both wings, as further described. In Fig. 2^a which is a modification

of Fig. 2, two tubes 5 and 5^a are shown, one sliding into the other is pivoted at 6 to the frame and the other at 7 to the wings or planes they contain together 3 springs of 60 which the center one alone is compressed when the wing goes downward (therefore it must be stronger than the other two). When the wings or planes are forced upward, the piston 4 compresses the top spring, and the 65 inner tube 5 compresses the bottom spring as will be obvious from the drawing. The stays or what I may term "spring cables" are strong enough to support the weight of 70 wings and the load in flight and also not to 75 be affected by a moderate gust of wind but they will be sensitive enough to act as shock-absorbers in the case of a gust of wind of sufficient strength to imperil the transverse equilibrium of the machine. In addition to 80 the shock absorbing stays or "spring cables" I provide "reinforcing springs" 10 preferably of spiral form, which will only come into their strongest action when the spring cables have reached a certain degree of extension. If using ordinary spiral springs 85 they will be in two portions, which will separate from each other as shown in Fig. 2 as the wings move. These reinforcing springs will be of any well known kind whose normal tension can be regulated, especially those above the pivot of the wings, as 90 they will have to possess an excess of power sufficient to compensate for the weight of load. As the load will vary, the theoretical 95 100 105 110 115 120 125 130 135 140 145 150 155 160 165 170 175 180 185 190 195 200 205 210 215 220 225 230 235 240 245 250 255 260 265 270 275 280 285 290 one wing to the under portion of the other wing (or set of planes), whereby the springs of both wings take equal share of "wind absorption" and automatic lateral equilibrium 5 is thus insured. This cross-connection consists, in one form, of cables 11 running on pulleys 12 and following the direction of the arrows if a wing is forced upward and the reverse direction if a wing is forced downward. These cables 11 could be directed on more pulleys so as to be clear of the body. In Fig. 4 an alternative application of this principle of reciprocal transmission of any extra air-pressure is obtained by two crossed 10 cables or chains, or pivoted rods (13), attached to segments 14, or, for greater strength, to triangles as shown in dotted lines, fixed to the wings in obvious manner. Instead of cross-connections single ones 15 could be used. Referring now to Fig. 6 which shows how the system of absorbing springs to limit oscillations and to take the thrusts of gusts of wind may be applied to a biplane: 15 are the planes and 10 the springs 20 or their modification shown in Fig. 2^a. These planes are hinged as shown at 16 and the devices shown in Figs. 1 to 4 for the reciprocal movement of the planes may be used in connection with these planes. One 25 of the advantages of my articulated wings or planes is that their span need not be so great as that of the existing rigid type of machines and therefore it will be possible to wheel the improved aeroplane on a road. 30 The planes both in Figs. 6 and 8 are provided with what I may term "air sluices", that is to say apertures 16' with doors 17 whereby these apertures may be opened simultaneously on the two sides of the machine by a cord or the like 18, which will enable the machine to descend while maintaining its horizontality and whether stopping the motor or not. It is not intended 35 that these air-slutes or valves should be independently operated on either side of the machine for balancing laterally. Opening the sluices of both wings simultaneously, decreases equally the carrying capacity of both wings (or pair of wings in a biplane) 40 and as aforesaid allows of the aeroplane being lowered without dipping. The pulling cords or wires of the air-slutes will have enough extra length hanging loose so that the sluices will not be opened by any oscillations of the wings. The doors are normally kept closed by a spring 19 and a catch 20 of any suitable design and in a well-known manner. It will be understood 45 that in a biplane there will be four sluices (a pair of which are shown in Fig. 6.) In this figure, the main wire 18 branches into two wires *a* and *b*, which are connected obliquely to the spring catches 20. I am aware that it is not new to provide aper-

tures in the wings or planes of aeroplanes 55 having valves or doors therefor which are pivoted on axes parallel to the line of flight and adapted to be independently operated at either side of the machine for balancing laterally. 70

Referring now to Figs. 5. and 7. which illustrate my improved elevator and automatic longitudinal stabilizer, this consists of a plane 25 pivotally suspended as at 26 from the frame 1. It is placed well-ahead 75 of the fuselage and preferably higher than the center of gravity of the aeroplane and being freely suspended will tend therefore to remain in a horizontal position instead of following the inclination of the aeroplane 80 when the latter has a tendency to dip at the front end, and the action of the weighted bar *c* at the rear end will push the front-end upward, thereby checking automatically the diving movement. As 85 a controlled elevator, this little plane will serve to start or raise the aeroplane, through its front-end being raised by the pilot with control-wires 27. To keep this stabilizer horizontal in normal flight, a cross-bar 29 90 on the frame 1. prevents it from oscillating upward at the rear-end, and it is retained against this crossbar by the air-pressure (due to speed) on its downwardly-turned end. The upwardly-turned front-end is to 95 give the plane a tendency to rise. A similar stabilizer may be used at the rear, except that its ends may not be bent, at least its front end; its weighted bar will be under the front-end, and the fore-portion may 100 preferably be longer than the rear portion.

I claim—

1. In an aeroplane, a horizontal rudder pivotally and freely suspended from the frame with its front end upturned and its 105 rear end downturned, and means to limit the upward tilting of the rear end whereby to cause the same to act as a stabilizer.

2. In an aeroplane, a horizontal rudder pivotally suspended from the frame with its 110 front end upturned and its rear end downturned and weighted, and means to limit the upward tilting of the rear end whereby to cause the same to act as a stabilizer.

3. In an aeroplane, wings articulated to 115 the frame and normally disposed at a dihedral angle, stays connecting the wings to the frame, springs interposed in the stays, and an unyielding flexible connection between opposite wings whereby to cause the 120 same to move upwardly or downwardly in unison.

In testimony whereof I affix my signature in presence of two witnesses.

PAUL DE CREQUY.
